UNITED STATES PATENT OFFICE.

FRANCIS J. DOWLING, OF NEW YORK, N. Y.

PINCUSHION.

1,229,051.

Specification of Letters Patent. Patented June 5, 1917.

Application filed January 9, 1917. Serial No. 141,375.

To all whom it may concern:

Be it known that I, FRANCIS J. DOWLING, a citizen of the United States, and a resident of the city of New York, borough of 5 Manhattan, in the county and State of New York, have invented a new and Improved Pincushion, of which the following is a full, clear, and exact description.

This invention relates to pin cushions or 10 other analogous ornamental devices and has particular reference to the mechanical construction or assemblage of the several parts constituting the body or frame of the cushion.

15 Among the objects of the invention is to provide a simple, cheap, easily manipulated and reliable means for gripping and holding the resilient part of the cushion or the cushion proper.

20 Another object of the invention is to provide a base or frame adapted for the utilization of a plurality of bivalve shells, constituting the jaw portions or parts that hold the cushion.

25 With the foregoing and other objects in view the invention consists in the arrangement and combination of parts hereinafter described and claimed, and while the invention is not restricted to the exact details of 30 construction disclosed or suggested herein, still for the purpose of illustrating a practical embodiment thereof reference is had to the accompanying drawings, in which like reference characters designate the same 35 parts in the several views, and in which—

Figure 1 is a perspective view showing one form of my improvement complete;

Fig. 2 is a vertical transverse section of the same;

40 Fig. 3 is a plan view of another form of my invention with the cushion removed to show the appearance of the interior of the jaw devices;

Fig. 4 is a perspective detail view of the 45 frog shown in Fig. 3;

Fig. 5 is a vertical central section on the line 5—5 of Fig. 3;

Fig. 6 is a sectional detail view of a further modification;

50 Fig. 7 is a detail perspective view of a frog modified in form slightly from that of Fig. 2; and

Fig. 8 is a bottom plan view of the form shown in Fig. 6.

55 Referring now more particularly to Figs. 1 and 2, I show a pin cushion comprising a

base 10, a pedestal 11, a plurality of jaws 12, and a cushion proper 13, together with attachment devices holding the several parts in place with respect to one another. 60

The base and pedestal portions may be made of any suitable material or any desired configuration, but for the purpose of this description they may be regarded as being made of wood and adapted to be 65 secured firmly together by a plurality of screws 14 extending through countersunk holes 15 in the base.

The pedestal is provided in its upper surface with a depression or pit 16, through 70 the bottom of which is bored a hole 17 for a binding bolt 18, the lower end of which projects preferably into a hole 19 bored or otherwise formed in the central portion of the base 10. This hole facilitates the centering 75 of the pedestal upon the base when assembling the parts. The hole 17 is counterbored at 20 to receive the washer 21 and nut 22. The head and shoulder portions of the bolt coöperate with the frog 23 having hook-shaped ends engaging over the knob portions 24 of the shells or jaws. The shoulder portions 25 of the jaws bear upon the rim portion of the pit 16, and hence when the bolt is tightened drawing downwardly 85 forcibly upon the frog, the outer edge portions 26 of the shoulders or jaws are caused to swing toward each other and embrace the cushion 13 in the manner indicated with sufficient force to positively retain the 90 cushion in place.

The cushion 13 may obviously be constructed from any suitable fibrous or resilient material 27, inclosed within a bag or casing 28 and having an ornamental facing 29 where it is exposed to view. Likewise the base and pedestal portions of the device may be finished or ornamented in any suitable manner as, for example, by coverings 30 and 31, the edges of which are tacked or otherwise fastened to the respective parts along the plane of contact between them. I also prefer to employ a piece of ornamental cord or gimp 32 around the meeting edge of the base and pedestal, said cord being 100 partially embedded in the rabbet formed around the edge of the pedestal.

In assembling the device, the cushion is gripped within the jaws by coöperation of the bolt through the pedestal 11 and then 110 the base portion is applied to the pedestal through the operation of the screws 14. All

fastening devices, therefore, are practically invisible in the finished article.

5 In the form of the invention shown in Figs. 3 and 5, the main features are similar to those in Figs. 1 and 2, there being shown the base and pedestal members 10 and 11', adapted to be secured together by screws 14. This form of the invention, however, is one providing for the use of four jaws or shells 10 12' instead of two, the form of the pit 16' being modified accordingly, as is also the frog 23'. The gripping and rolling action with respect to the frog and the shoulder portions of the jaws is the same in all forms 15 of the invention.

While I have found in experience that natural bivalve shells, such as indicated at 12, are suitable both as to ornamental appearance and practical strength, it is obvious 20 that the jaws might be formed artificially and of various designs, so long as the operation of the device remains substantially the same. The base or pedestal portions also of the device, as intimated above, 25 may be made of other material than wood such, for example, as plaster of Paris, high grade concrete, glass or the like. If made of plastic material, the base and pedestal may be combined into one member or base 30 10', as indicated in Figs. 6 and 8. This member is formed with a pit 16', a countersunk hole or opening 20 in its bottom, and a central hole 17 for the binding bolt 18. The washer 21' in this form of the invention 35 is preferably cruciform, having its ends arranged beneath or opposite the several shoulder portions 25 of the jaws for additional strength of the device.

The central portions of the frogs may be 40 plane, as indicated in Fig. 2, or depressed, as indicated in Figs. 4 and 7, the latter showing a two-hooked frog 23^a, which might be substituted for the one shown in Fig. 2. With the shoulders or jaws formed 45 as shown and anchored in place in the manner indicated, it is impossible for any one of them to become loose and hence they co-operate with one another to hold the cushion in fixed position reliably.

50 I claim:

1. In a pin cushion, the combination of a support having a pit formed therein, a plurality of curved jaws having their shoulder portions bearing in said pit, each jaw

having an inwardly and upwardly projecting knob, a member having hooks spanning the space between the knobs of the jaws and hooking over the same, means anchoring the last mentioned member to the support and causing the rolling of the jaws at their free edges toward one another, and a cushion embraced within said jaws. 55 60

2. In a pin cushion, the combination of a support having a pit formed in its upper surface and a hole extending downwardly 65 from the center of the pit, a plurality of convex jaw members having rounded shoulder portions fitted within the opposite sides of the pit, the jaw members being adapted to roll around their points of contact with the support, toward the central axis thereof, means engaging the lower and inner edge portions of the jaws and serving to draw the same downwardly, causing the jaws to roll with their free edges toward 70 each other, and a cushion arranged and held between the free edges of the jaws. 75

3. In a pin cushion, the combination of a rigid support having a pit formed in its upper surface with a rounded rim and a central hole therethrough, a plurality of bivalve shell-shaped jaws supported with their rounded shoulder portions in the curved rim of the pit, the knob portions of the jaws projecting inwardly toward the axis of the hole, a frog having hook-shaped ends engaging over and interlocking with said jaw knobs, screw means acting through the frog drawing it downwardly toward the bottom of the pit and causing the rolling of 85 the free portions of the jaws toward one another, and a resilient cushion gripped between said free portions of the jaws. 90

4. In a device of the character set forth, the combination of a support having a pit formed therein, a plurality of jaws having rounded shoulder portions bearing in said pit, each jaw having inwardly and upwardly projecting knobs, a frog having hooks spanning the space between the knobs of the jaws and engaging over the same, adjustable anchoring means securing the frog to the support and causing the movement of the jaws at their outer free edges toward one another, and a member embraced within the jaws. 95 100 105

FRANCIS J. DOWLING.
